UNITED STATES PATENT OFFICE.

WILLIAM E. WINE, OF TOLEDO, OHIO.

VENTILATOR.

Application filed July 19, 1922. Serial No. 575,923.

To all whom it may concern:

Be it known that WILLIAM E. WINE, a citizen of the United States of America, residing at Toledo, in the county of Lucas and 5 State of Ohio, has invented certain new and useful Improvements in Ventilators, of which the following is a specification.

My invention relates to new and useful improvements in freight car ventilators, and 10 more especially to ventilators which are designed to be installed in freight cars having the "steel ends."

One of the principal objects of the invention is to provide a ventilator comprising 15 a frame made up of four pieces, each of said pieces being provided with a front and rear flange which are designed to respectively register when the frame is assembled, each of said pieces, also, being provided with certain end flanges which abut when the frame is assembled so that the frame may be quickly riveted to form substantially a unitary structure.

Still another object of the invention is to 25 provide a ventilator comprising a frame (which is designed to be easily riveted to the steel end of the freight car) in which there are cross pieces, to form a plurality of openings, in which openings are placed a plurality of shutters which may be readily operated; the formation of the openings being such that it will be impossible for rain or snow to enter through the ventilators.

With these and other objects in view, the 30 invention consists in certain new and novel arrangements and combination of parts, which will be hereinafter more fully described and pointed out in the claims.

Referring now to the drawings showing 40 a preferred embodiment of the invention,

Fig. 1 is a view in elevation showing the ventilator installed in a freight car having a steel end.

Fig. 2 is a sectional view taken just above 45 the bottom rail of the ventilator with the shutters removed for the sake of clearness.

Fig. 3 is a vertical sectional view showing the shutters of the ventilator in their closed position.

Fig. 4 is a similar view with the shutters shown in their open position.

Fig. 5 is a sectional view taken on line 5-5 of Fig. 3, and

Fig. 6 is a fragmentary perspective of one 55 of the shutters.

Referring now more in detail to the sev-

eral views, there is shown fragmentarily an upper central section of a steel end 1, provided with the usual corrugations 2 and 3, the plane surface being cut out for the reception 60 of the ventilator 4.

In most freight cars having steel ends a similar lower section is provided in which there will likewise be inserted a ventilator.

Referring now to the ventilator, it will be 65 seen that it comprises a frame 5, which is made up of the upper and lower rails 6 and 7 respectively, and the side pieces 8 and 9.

This frame may be malleable iron or steel and is preferably provided with a flange 10 70 along its front edge and a flange 11 along its rear edge; that is, each of the four parts of the frame are provided with these flanges which register when the frame is assembled.

To form abutting fastening surfaces for 75 the several parts of the frame, the upper and lower rails 6 and 7 are provided with the end pieces 12 while the side rails have the flanged portions 13 which will be tightly riveted to the aforementioned ends 12 as 80 may be seen in the several views.

The flange 10 on the outer portion of the frame may be scalloped for lightness and the rivets will be passed through this flange and through the edges around the opening 85 of the steel end 1 so that the ventilator will be tightly held in place. In Figs. 3 and 4, are shown the cross beams 14 of the end of the car together with the inner sheathing 15, the ventilator fitting snugly between the 90 cross beams and abutting against this inner sheathing 15.

The several pieces of the frame may also be braced or strengthened by the flanges 16 95 shown in the dotted lines of Fig. 1.

As far as the specification has proceeded, it will be seen that the frame is one that may be quickly and readily assembled, is extremely rigid and is especially designed to be placed behind a steel end and riveted 100 thereto.

Still referring to the frame, and now more especially to the side rails 8 and 9, as clearly shown in Figs. 3 and 4, they are each provided on their inner surface with the pairs 105 of arcuate guides 17 for the ends of the shutters 20 and radially disposed U-shaped bearings 18 for the reception of the pintles 19 of the shutters.

Extending across the ventilator are the 110 divisional strips 21 which have the T-shaped flanges 22 at their upper extremities and the

2
U-shaped abutment 23 at their lower edges while their opposite ends are flanged as at 24 so that these strips may be quickly riveted to the side pieces 8 and 9 of the frame 3 of the ventilator.

Referring now to the shutters 20, it will be seen that they are arcuate, each having the upper flange 25 and the lower flange 26, the ends being provided with the pintles 19, 16 heretofore referred to, to rest in the bearings 18.

Referring for a moment to the upper rail 6, it will be seen that it is provided with a U-shaped flange 27 so that the flange 25 of 15 the upper shutter will abut against the same when the shutter is in its closed position, and the flange 25 of the other shutters will abut against the U-shaped abutments 23 of the divisional strips 21, as clearly shown in 20 Fig. 3.

Placed centrally of the ventilator, and in a vertical position is the arm 28 having the openings 29 therein for the reception of cotter pins which are also designed to pass 25 through the opening in the lugs 30 formed to the rear and centrally of each shutter. The operation, therefore, of this arm 28, will open and close all of the shutters simultaneously. The shutters will be guided 30 or held from excessive vibration by the arcuate tracks 17 which enclose the ends of the shutters 20, as heretofore mentioned.

A lug 31 is also provided centrally of the lower cross piece 22 and a lug 32 is formed 35 on the arm 28 so that the shutters may be sealed in their open position, as shown in Fig. 4, or may be sealed in their closed position, as shown in Fig. 3, by passing the seal around the arm 28 and through the 40 lug 31.

When the shutters are in their open position as shown in Fig. 4, it will be impossible for any rain to enter the car as the shutters will deflect the same, and as the cross 45 pieces 22 are angularly disposed, no rain can blow through the ventilator into the car.

A netting 33 may be bolted across the front of the ventilator, if desired, to keep out birds or insects.

From the foregoing it will be seen that I 50 have provided a ventilator which may be quickly and readily assembled, and which

may be easily installed in a freight car having steel ends, it necessitating simply the cutting out of the steel end to a correct size 55 and riveting the flange of the ventilator thereto.

It will also be seen that I have provided a ventilator which is very rigid in construction, relatively light in weight, may be 60 quickly and readily assembled and relatively cheap to manufacture.

Many slight changes might be made without departing from the spirit and scope of 65 the invention.

I claim—

1. A ventilator comprising a frame consisting of two side pieces and an upper and lower rail, upright spaced flanges formed on said upper rail and downwardly extending spaced flanges formed on said lower rail, said side pieces provided with outwardly extending spaced flanges and the 70 said flanges of the several parts registering when said frame is assembled, said side pieces also provided with flanges near their ends to be secured to the end pieces of the upper and lower rails.

2. A ventilator comprising a frame consisting of an upper and lower rail and two side pieces, all of said pieces provided with a front and rear flange which register when 75 said frame is assembled, and the front flange on the upper rail, and the front flange on the lower rail being greater in depth than the rear flanges on the upper and lower rails, further flanges formed at the upper and lower ends of said side pieces and on 80 their inner surfaces, and secured to the ends of the upper and lower rails.

3. A ventilator comprising a frame formed of an upper and lower rail and two side pieces, all of said pieces provided with a front and rear flange which respectively 85 register when said frame is assembled, further flanges formed at the upper and lower ends of said side pieces and on their inner surfaces and adapted to be secured to the ends of the upper and lower rails, means 90 extending across the ventilator to provide angular passageways, and add rigidity to the frame.

In testimony whereof I affix my signature.
WILLIAM E. WINE.
